UNITED STATES PATENT OFFICE

91,319

DESIGN FOR A TIE RACK

Abraham Falk, Flushing, N. Y.

Application November 10, 1933. Serial No. 49,689

Term of patent 7 years

To all whom it may concern:

Be it known that I, ABRAHAM FALK, a citizen of the United States, residing at 36-40 Boune St., Flushing, L. I., N. Y., have invented a new, original, and ornamental Design for a Tie Rack, of which the following is a specification, reference being had to the accompanying drawing, shown forming a part thereof.

In the drawing:

Fig. 1 is a front view of a tie rack showing my new design.

Fig. 2 is a side view.

Fig. 3 is a top plan view.

I claim:

The ornamental design for a tie rack as shown.

ABRAHAM FALK.
